CLOTHES WRINGER

Frederick R. Mokrohajsky, Binghamton, N. Y., assignor of one-half to Martin J. Eckert, Binghamton, N. Y.

Application October 31, 1936, Serial No. 108,624

3 Claims. (Cl. 68—267)

My invention relates to improvements in clothes wringers and has for its principal object the provision of a belt feeding means for the clothes to and from the squeegee rollers whereby the clothes are transported from a point well away from such rollers to the same and thence away from the rollers without the necessity of bringing the hands for fingers into close proximity to the rollers. This provides a safety factor for clothes wringers which materially reduces the danger and likelihood of pinched fingers and mangled hands.

Another object of my invention lies in the provision of a novel and efficient arrangement for the conveyer belt in combination with the rollers and with the cover plate which forms a guide to and from the rollers.

Still another object of my invention lies in the provision of improved drainage means whereby the water run off is controlled and guided with relation to the wringer.

Other objects and advantages will be apparent as the description proceeds, reference now being had to the figures of the accompanying drawings, forming a part of this application, and wherein like reference characters indicate like parts.

In the drawings:

Figure 1 is a front view of a wringer embodying my invention.

Figure 2 is a bottom plan view of the wringer.

Figure 3 is a top plan view of the wringer, a portion of one of the cover plates being broken away for clearness of illustration.

Figure 4 is a detail cross sectional view taken on the line 4—4 of Figure 1.

Although I have shown my invention as applied to one particular type and construction of wringer, it will be understood that the same is not to be limited to this particular form but is of wide application on wringers of various constructions.

The reference character 1 indicates generally a clothes wringer provided with a top protecting cover 2 and adjusting means 3 therefor. The squeegee rollers 4 are suitably supported in the sides of the wringer frame and may be provided with any suitable or desired type of driving means either for hand or motor operation.

The underside of the wringer is provided with a frame plate 5, to the upper side of which is suitably secured a drainage plate 6 projecting forwardly and rearwardly of the frame plate 5 and the free edges of which drain plate slope downwardly from the center plate 5. The side edges 7 of the drain plate are flanged upwardly to

guide and direct the water from the rollers to the outer free edge of the plate from which it runs off into the tub or other receptacle provided therefor.

On the underside of the drain plate 6 and adjacent each free edge thereof there is provided a flanged roller 8 supported in suitable bearings 9 secured to the plate 6 as by screws 10. The free edges of the plate 6 are notched or cut away as at 11 (see Figures 2 and 3) such cutaway portions exposing the rollers 8 from the upper side of the drainage plate 6.

The upper side of the drain plate 6 is provided with a channel shaped flange 12 extending around the cutout portions 11 which flange serves to direct the water running down the plate around the ends of the rollers 8 and protects such rollers from the water running down off the plate.

The rollers 8 are in alignment with each other and with the approximate center of the squeegee rollers 4. The length of the guide rollers 8 is substantially less than the length of the squeegee rollers 4 and extending around such guide rollers 8 and between the squeegee rollers 4 is an endless carrier belt 13. The width of this belt is substantially the same as the length of the guide rollers 8 between the flanges thereof and the belt is formed of any suitable material for frictionally engaging and carrying up to the squeegee rollers 4 on one side, the clothes placed on such belt by the user, and carrying such clothes away from the rollers 4 on the opposite side. The belt serves to feed the clothes into and through the wringer rollers 4 and away from the same.

The bottom squeegee roller 4 is provided at the point where the belt 13 passes thereover with a groove 14 of a depth of approximately half the thickness of the belt, whereby the belt is guided around the roller and also permitting the rollers to be adjustably pressed together for wringing the clothes without material interference from the belt.

Referring to Figure 2 it will be noted that there is mounted as at 15 upon the plate 5 a bracket 16 upon which is pivotally mounted a tension roller 17 engaging the belt 13 and forced into resilient contact therewith by means of the leaf spring 18 pressing against a bar 19 carried by the roller arm. This keeps the belt constantly under tension.

Suitably mounted upon the frame of the wringer are the cover or guiding plates 20 provided with side and front flanges 21 to enclose the drain plate 6. The inner free edges of the guiding plates 20 extend upwardly on a slope to a point

immediately adjacent the lower wringer roller 4, terminating at a point slightly below the line of engagement of the two wringer rollers.

The free inner edges of these guiding plates 28 are cut out centrally as at 22 and the edges of the cutout portion are turned or rolled inwardly to provide smooth even edges around the same.

The angle of the belt 13 from the guide rollers 8 upwardly to the wringer rollers 4 is such as to bring the belt 13 outside of the cover plates 20 in a position to overlie the free edges of such plates. This provides a strip of belt extending from the inner edge of the cutout portions 22 of the cover plates up to the wringer rollers 4 in an accessible feeding position where clothes can be placed thereon at a point well away from the wringer rollers and carried by such belt to the wringer rollers while passing therebetween, and thence away from the rollers onto the cover plate on the opposite side—well away from the rollers.

Obviously water which is squeezed from the clothing by the wringer rollers drops downwardly between the rollers and the cover plates 20 on to the drainage pan 6 where it is guided downwardly and outwardly to the free edge thereof around the channel flanges 12 and away from the guide rollers 8 and belt 13. Thus the belt is kept free of the water from the clothes except at the actual point of wringing.

It may be observed also that any water which runs down the strip of belt 13 between the rollers and cutout portions 22 of the guiding plates 28, passes beneath such plates, sufficient space being left between the cover plates and the belt for this purpose.

It will thus be seen that I have provided a

means for receiving and guiding clothes to and from the rollers of a wringer without bringing the fingers or hands into close proximity therewith as well as means for protecting the belt and guide rollers against saturation by water during the wringing operation.

Of course, changes may be made in details of construction and arrangement of parts without departing from the spirit and scope of my invention. I do not limit myself, therefore, to the exact form herein shown and described, other than by the appended claims.

I claim:

1. A wringer comprising a frame, squeegee rollers therein, an endless belt disposed to pass between said rollers substantially centrally thereof for feeding clothes to said rollers, and a guiding plate, a part of said belt overlying a portion of said cover plate adjacent said rollers.

2. A wringer comprising a frame, squeegee rollers therein, an endless belt disposed to pass between said rollers substantially centrally thereof for feeding clothes to said rollers, and a guiding plate, portion of said belt overlying a portion of said guiding plate adjacent said rollers, said guiding plate having a cutout portion adjacent said rollers through and over which a portion of said belt passes to said rollers.

3. A wringer comprising a frame, squeegee rollers therein, an endless belt disposed to pass between said rollers substantially centrally thereof for feeding clothes to and from said rollers, guiding plates adjacent said rollers and sloping away from the same, a portion of said belt overlying a portion of said guiding plates adjacent said rollers.

FREDERICK R. MOKROHAJSKY.
